UNITED STATES PATENT OFFICE

141,228

DESIGN FOR A TOWEL CABINET OR SIMILAR ARTICLE

Jacques Roussou, Los Angeles, Calif.

Application March 13, 1945, Serial No. 118,450

Term of patent 14 years

(Cl. D33—18)

To all whom it may concern:

Be it known that I, Jacques Roussou, a citizen of the United States and a resident of the city of Los Angeles, county of Los Angeles, and State of California, have invented a new, original, and ornamental Design for a Towel Cabinet or Similar Article, of which the following is a specification, reference being had to the accompanying drawing, forming a part thereof.

Fig. 1 is a side elevational view of the towel cabinet or similar article showing my design; and Fig. 2 is a front elevational view thereof.

Fig. 3 is a top plan view.

I claim:

The ornamental design for a towel cabinet or similar article, as shown.

JACQUES ROUSSOU.
